FLASK

Arne Erkers, Styckjunkaregatan 7, Stockholm, Sweden

Filed Apr. 29, 1964, Ser. No. 79,734

Term of patent 14 years

(Cl. D58—8)

Fig. 1

Fig. 3

FIG. 1 is a front perspective view of the flask, showing my new design;

FIG. 2 is a side elevational view of the flask; and

FIG. 3 is a bottom plan view of the flask.

I claim:

The ornamental design for a flask, as shown.
